UNITED STATES PATENT OFFICE.

THOMAS A. RONSTROM, OF CHICAGO, ILLINOIS.

HEATING APPLIANCE.

1,307,332.

Specification of Letters Patent. Patented June 17, 1919.

Application filed October 24, 1917. Serial No. 198,195.

To all whom it may concern:

Be it known that I, THOMAS A. RONSTROM, a subject of the King of Sweden, residing at Chicago, in the county of Cook and State of Illinois, have invented certain new and useful Improvements in Heating Appliances, of which the following is a specification.

This invention relates to improvements in heating apparatus and more particularly to an arrangement of the casing within which is mounted the burner and heat receiving medium.

One of the objects of my invention is to increase the efficiency of heating apparatus so as to eliminate a large percentage of the waste heat which normally passes out with the products of combustion through the stack or flue.

One of the principal objects of this invention is to provide a construction in which the greatest heat transferring efficiency is secured. Theoretically, in order to secure perfect efficiency the waste gases which emerge from the casing surrounding the burner and heat absorbing element should contain no heat, or from a practical standpoint should be at atmospheric temperature. This is not practically possible but in the construction here disclosed the result is approximated. The desired result is secured by proportioning the area of the upper waste gas outlet so that it will be sufficient to pass a volume corresponding to that of the waste gases at their pressure at the exit point. When so restricted in area the flow of fluid through the casing will be materially restricted; if no other means were provided for the escape of gases than through the permanently restricted upper outlet, there would be occasions when the production of waste gases would be increased and therefore such gases would be prevented from escaping with sufficient rapidity and the burner would be surrounded by non-combustible gas. These gases would restrict combustion and the heating fluid would be delivered through the burner without being entirely consumed.

To this end I have provided a series of openings located above the burner in such position that upon an increase in the amount of fuel consumed, the increased volume of waste gases will not be permitted to surround the burner and retard the efficiency of combustion. It will be seen, therefore, that

there is a distinct coöperation between the location of the lateral openings at a point above the burner and the size of the escape opening in the top of the casing. Being located as described at a point just above the burner, there is no possibility of or opportunity for interference with the efficiency of the burner when, due to fluctuation of fuel pressure, the pressure within the casing, due to the restricted outlet opening, becomes greater than atmospheric, and the excess pressure will pass out of the casing through the lateral openings.

By reason of the provisions described, the speed of passage of gases through the casing is materially reduced and I am therefore able to retain the heated gases in contact with the coils for a much longer period. Neither are the waste gases diluted with atmospheric air as during normal operation no atmospheric air will enter through the lateral openings. The restriction of the exit opening does not serve to materially increase the pressure within the casing as in view of the increased rate of absorption, the pressure of the gases is constantly reduced.

Stated in a few words, however, the advantageous result is secured by so restricting the waste gas outlet that there is constantly maintained within the casing a volume of gas which is relatively highly heated and which is in intimate contact with all the convolutions of the coil, the only gases escaping through the outlet being those from which the maximum of heat has been absorbed and which are forced out by the ascending current of gases from the burner. The lateral openings have the function of equalizing the pressure between the interior and exterior of the casing. Should the pressure increase due to the restriction of the outlet area, this excess pressure can escape at a point above the burner without restricting combustion and thereby lessening the efficiency of the burner.

Still other and further objects will become readily apparent to those skilled in the art from a consideration of the following description and drawing wherein;

Figure 1 is a side elevation of a water heater embodying my invention.

Fig. 2 is a vertical sectional view through the water heater shown in Fig. 1.

For the purpose of making a complete disclosure of the invention, I will illustrate and describe the application of my invention to

a gas water-heater of a well known type such as is commonly used to supply hot water for domestic purposes.

With the ordinary type of water-heater, a 5 casing is provided for inclosing the heating coils and burner. Such casings are provided at their tops with a flue or chimney through which the products of combustion are permitted to escape. The coil is mounted within 10 the upper portion of the casing and at the lower end a burner is positioned for generating heat. The casings are usually provided near the bottom below the burner with openings for the admission of air. I have found 15 from study and experimentation, that the openings usually provided in the bottom portion of the casing admit a large quantity of air, greatly in excess of that needed for perfect combustion of the gas and consequently cause a strong, up-draft carrying out 20 through the stack a great deal of heat which might otherwise be used for raising the temperature of the water within the coils.

When a sufficient quantity of air is mixed 25 in the proper way with the combustible gas, the maximum heat generating efficiency is reached, and the introduction of more air will only serve to increase the volume of the gases of combustion without increasing the 30 generation of the heat.

In an apparatus of this character it is desirable to have the products of combustion pass through the heater in as concentrated form as practicable and each cubic foot of 35 gases, containing a certain number of heat units, will transmit more of its heat to the water heating coil, than if the same number of heat units were carried by a larger volume of gas.

40 For the purpose of a better understanding of the explanation of the theory upon which my invention is based, I will first describe the simple apparatus which I have illustrated in the drawing. The numeral 10 indicates a semi-cylindrical vertical shell, cut away at its front portion to receive a hinged door 11. A closed base 12 is secured to the bottom of the shell 10 and at the top is provided a cap 13 with which the flue 14 makes 45 engagement. A damper 15 is mounted within the flue and is controlled by a handle 16. A burner tube 17 projects through the bottom 12 carrying a burner plate 18 on its upper end, its lower end being provided with 50 an air mixer 19, within which the gas fed through the pipe 20 is mixed with a proper quantity of air. A heating coil 21 is positioned within the upper portion of the casing and slightly above the top of the burner 55 flame, I have provided a number of openings 22 in the wall of the casing and door. To simplify the explanation of my invention, I will divide the space within the heater casing into two imaginary sections; (a) 60 comprising the area extending from the bot-

tom of the heating casing to a slight distance above the top of the flame, and area (b) extending from the top of the bottom section (a) to the top of the casing. Above this upper section, I provide a damper for 70 choking off the free passage of the gases of combustion from the casing thus causing a congestion of the gases throughout this upper section permitting a longer period of time within which they can give up heat to 75 the water coil than would otherwise be the case.

By gradually closing the damper, it is possible to obstruct the outflow of gases from the casing until a point is reached 80 where the congestion of gases, surrounding the water-coil, will extend downwardly to a point slightly above the top of the burner flame. If the closing of the damper is continued beyond this point, it will be apparent 85 that this area will be lowered to a zone interfering with the free combustion and consequently reducing the efficiency of the burner. If the operating conditions, such as air density, gas pressure and quality were 90 always constant, it would be possible to adjust the damper until the zones (a), (b) were established as indicated in the drawings, and then continue the operation of the heater at this highly efficient adjustment. 95 Such conditions, are, however, impossible of attainment, and I have therefore found it necessary to provide auxiliary outlet openings positioned at the plane in which the two zones meet. These openings permit the 100 outflow of gases of combustion in the event the upper zone (b) tries to creep down into the zone (a).

Normally, with proper adjustment, there will be neither inflow nor outflow through 105 these auxiliary openings, their purpose being solely to provide for variations in operating conditions and to prevent interference with proper combustion.

Whereas I have illustrated and described 110 but a single embodiment of my invention, it will be apparent to those skilled in the art, that various changes and modifications may be made therein, without departing from the spirit of the invention, or the scope of the 115 appended claims.

Having described my invention, what I claim is:-

1. In a device of the class described, the combination of a casing having a closed 120 lower end and a waste gas outlet in its upper end, a combustion space being provided in the lower portion of the casing and a heat absorbing space in the upper portion, a water container in the heat absorbing space, 125 a burner in the combustion space, all the air necessary for combustion being supplied through the burner, the casing being provided with a plurality of side openings located at a point above the combustion space 130

and below the heat absorbing space, and means for so restricting the waste gas outlet that the velocity of the waste gases is materially reduced, any abnormal excess of waste 5 gas escaping through the side openings, thereby being prevented from restricting the flame, substantially as described.

2. In a device of the class described, the combination of a casing having a closed 10 lower end and a waste gas outlet in its upper end, a combustion space being provided in the lower portion of the casing and a heat absorbing space in the upper portion, a water container in the heat absorbing space, 15 a burner in the combustion space, all the air necessary for combustion being supplied through the burner, means for regulably restricting the waste gas outlet and increasing the pressure in the heat absorption space 20 thereby reducing the velocity of the gases therethrough and increasing the pressure therein, and means for preventing an increase of pressure in the combustion space, said means including an opening in the casing 25 located at a point above the combustion

space and below the heat absorption space, substantially as described.

3. In a device of the class described, the combination of a casing having a waste gas outlet in its upper end, a damper in said 30 outlet, a burner projected into the casing through the bottom wall thereof, said bottom wall being otherwise imperforate, all the air necessary for combustion being supplied through the burner, a water container 35 within the upper portion of the casing, said damper serving as a means for reducing the velocity of the waste gases through the space occupied by the water container and thereby increasing the pressure in said space, said 40 casing being provided with a side opening located at a point intermediate its height and above the burner flame, said opening serving to prevent any increase of pressure in the combustion area by permitting the 45 escape of excess waste gases, substantially as described.

In testimony whereof I hereunto set my hand.

THOMAS A. RONSTROM.
